WALTER VAN B. ROBERTS, OF PRINCETON, NEW JERSEY, ASSIGNOR TO RADIO CORPORATION OF AMERICA, A CORPORATION OF DELAWARE

MEANS FOR ENERGIZING THERMIONIC TUBES

Application filed February 11, 1928. Serial No. 253,545.

This invention relates to a means for energizing thermionic devices and especially to a means for supplying plate, filament and grid potentials to a thermionic tube from a variable or fluctuating direct current source.

The present tendency towards energizing thermionic tubes is to energize the tubes, that is, to supply plate potentials, from a source of alternating current which has been rectified but not perfectly filtered or from a source of commutated direct current. The unidirectional current so obtained is not constant and smooth and, if a current-time curve were plotted it would easily be seen that there are fluctuations in the current supply due to either the rectification or the commutation of the current. This current may upon further consideration be said to consist of a constant current component and alternating current components superimposed thereon. When such a unidirectional current is fed through a resistance network and plate potentials are tapped therefrom, undesired results obtain; one of which, when the thermionic tube is used in connection with a radio receiving outfit for example, manifests itself in the telephones of the receiver as an annoying hum.

One of the objects of this invention, therefore, is to provide means whereby this and other effects due to the fluctuations in the direct current source, are substantially eliminated.

The fluctuations in plate potential, due to the fluctuations in current in the network, in turn vary the electron flow within the tube, and hence cause hum and other objectionable noises. This may be counteracted by applying to the input of the tube a voltage of a value and phase such that, whenever a momentary increase in plate voltage tends to increase the flow within the tube, the applied counteracting input voltage will tend to decrease the current within the tube, and vice versa. This may be accomplished by

connecting the plate and grid to points on the resistance network such that the voltage drop on the network between the point where the grid is connected and the means connection point of the filament on the resistance network is equal to the voltage drop between the plate and mean filament connection on the resistance network divided by the amplification factor of the tube.

If that is done, however, there will be no normal flow of current within the tube for the reason that the bias of the grid will be such that the electron flow will be completely choked. This in turn would mean that only the positive half of the wave applied to the input of the tube for amplification will cause a flow within the tube and is undesirable in the case of straight amplification where both portions of an input wave should be equally amplified.

Accordingly, it is a further object of this invention to provide means for securing a normal plate current flow, and to provide additional means in the output circuit for balancing out the harmful effects of the potential variations caused by the fluctuations in the direct current source utilized for energizing the tube. This is done by providing paths from the grid and plate of the tube to the network for maintaining a desired normal current flow, and by providing another alternating current path as the working output circuit of the tube, from its plate to the network, connected so that it is unaffected by the network current fluctuations.

The novel features which I believe to be characterized by my invention are set forth in particularity in the appended claims, the invention itself, however, as to both its organization and method of operation will best be understood by reference to the following description taken in connection with the drawing in which I have indicated diagrammatically one circuit arrangement whereby my invention may be carried into effect.

The invention will be more fully described hereinafter with the aid of the accompanying drawing in which I have illustrated the manner of connecting two stages of an audio frequency amplifier, for example, to a resistance network for obtaining therefrom current potentials for energizing the tubes and means for eliminating the effects of current variation in the network from affecting the output circuits of the tubes.

The figure diagrammatically shows how the effects of fluctuations in the network 2 energized from a variable unidirectional source of current 1, may be eradicated by plate connections. For the sake of brevity only two stages of an audio frequency amplifier have been shown although it is clear that the invention is applicable to all stages of radio and audio frequency amplification.

20 Telephones 26 and condenser 28 form an audio frequency path from the plate of tube 25 to network 2, and choke 27 forms a substantially direct current path to the network 2. Telephones, or other signal translating 25 devices, 26 are preferably placed in the alternating current path although they may be placed in the connection 36 between the plate and choke 27 which connection carries both the direct and alternating components.

30 Grid 29 is connected to point 30 in the network for obtaining a desired bias. Choke 27 is connected to network 2 at point 31 for obtaining a desired plate potential, that is, points 30 and 31 are chosen so that 35 tube 25 is operating on a desired point on its characteristic curve. Condenser 28 of large capacity is connected to point 32 on the network such that the voltage drop from point 32 to the midpoint of portion 33 of the net- 40 work 2 across which filament 34 of tube 25 is shunted, is equal to the product of the voltage drop from points 30 to the midpoint, of 33 multiplied by the amplification factor of tube 25. The elements of tube 25 are 45 similarly connected, the plate impedance, here the primary of transformer 35, being substituted for telephones 26.

It is thus seen that the effects of voltage variations between points 30 and 33 on the 50 electron stream of tube 25 are counteracted by an opposite voltage applied to the plate between points 32 and the midpoint of the portion 33, the opposing plate voltage being equal in numerical value and opposite in 55 sign to the voltage variation applied to the grid times the amplification factor of the tube. Input voltage variations through transformer 35 however, are unaffected and are readily amplified by tube 25 so as to actuate telephones 26. Similarly, the input to 60 transformer 35 is unaffected.

It is clear, of course, that resistance 2 need not be continuous or uniform throughout its length but may be composed of several 65 lumped resistances for the purpose of ob-

taining desired potential difference as indicated hereinbefore. The various taps such as 30, 30', 31, 31', 32 and 32' may be made adjustable and may be varied until desired operation of the system is had.

It is also clear that the filaments may be 70 connected in series with the remaining portions of the network 2 and not affect the operation of the system. It is preferred, however, to place the filaments across portions of the network 2 so that should one of them burn 75 out the filaments of the remaining tubes will remain incandescent thereby indicating the defective tube. The output circuits of the other stages of the system should be connected similarly to that of tube 25, with the exception that the plate coupling impedance should be substituted for telephones 26. The manner of doing so is indicated clearly by the 80 connections for tube 25.

The variation in voltage across portions 33 and 33' will not cause any appreciable hum as the thermal inertia of each of the filaments is such as to maintain the electron flow independent of the slight potential variations 90 across it.

While I have indicated and described only one system for carrying my invention into effect, it will be apparent to one skilled in the art that my invention is by no means limited 95 to the particular organization shown and described and that many modifications in the circuit arrangement may be used, as well as in the apparatus employed without departing from the scope of my invention as set forth in the appended claims.

Having thus described my invention what I claim is:

1. In apparatus of the character described, a resistance adapted to be connected to a 105 source of direct current, an electron discharge device having its cathode connected to an intermediate point on said resistance, and having its grid and anode connected to points on said resistance negative and positive respectively with respect to the cathode connection, said anode connection having a high impedance to direct current the ratio of the potential differences between the grid and cathode and the anode and cathode being substantially equal to the reciprocal of the amplification factor of said tube and a direct current connection from the anode to a point on said network having a positive potential.

2. In apparatus of the character described, a resistance network adapted to be connected to a source of unidirectional current, a plurality of thermionic tubes having grids, anodes and filaments, connections from the grids and filaments of the tubes to the network, and a plurality of connections from each anode to a plurality of points of different potential on said network, said last mentioned connections comprising means for se- 120 125 130

lectively passing alternating and direct current components, respectively.

3. In apparatus of the character described, a resistance network adapted to be connected to a source of unidirectional current, a plurality of thermionic tubes having grids, anodes and filaments, connections from the grids and filaments of the tubes to the network, and a plurality of connections from each anode to a plurality of points of different potential on said network, said last mentioned connections comprising means for selectively passing alternating and direct current components, respectively, the connections comprising means for passing alternating components being connected to points on the network such that the ratio of the anode-cathode potential drop on the network, to the grid-cathode potential drop on the network equals respectively the amplification factor of the respective tubes.

4. In apparatus of the character described, a direct current network, a thermionic tube, having its cathode connected to the network and its anode connected to two points on said network positive with respect to said cathode connection one of said anode connections having a high impedance to direct current and a low impedance to alternating current of audible frequency, and the other anode connection having a high impedance to alternating current.

5. In apparatus of the character described, a direct current network, means for connecting a source of potential in series therewith, a thermionic tube having anode, cathode and grid electrodes, means for connecting said cathode in parallel with a portion of said network, means for connecting said grid electrode to a point on said network, means for connecting the anode of said tube to a point on said network such that the voltage drop between said last named point and said filament is equal to the voltage drop between the point of connection of the grid to said network multiplied by the amplification factor of the tube and means for connecting said anode to a second point on said network, said two points on the network to which the anode is connected being of different potential.

6. In radio apparatus adapted to energize thermionic tubes, a resistance network, means for connecting a source of uni-directional current thereto, a thermionic tube having anode, cathode and grid electrodes, means for connecting said cathode in series with a portion of said resistance, a connection between the grid of said tube and a point on said network negative with respect to said cathode, and connections between the anode of said tube and two points on said resistance positive with respect to said cathode one of said anode connections including an element having a high alternating current impedance, the other anode connection having a low imped-

ance to alternating current of audible frequency.

7. In a cascade amplifier for audio frequency, a pair of thermionic tubes each having cathode, anode and grid electrodes, a network adapted to be energized by direct current, means for connecting the cathode of each of said tubes in parallel with different portions of said network, means for connecting the grid of each tube to a point on said network negative with respect to both of said cathode connections, and an alternating current and direct current path connecting the anode of each of said tubes to two points on said network positive with respect to said cathode.

8. In a cascade amplifier and a direct current network, means for connecting a source of potential in series therewith, a thermionic tube having anode, cathode and grid electrodes, means for connecting said cathode of said tube in parallel with a portion of said network, means for connecting the grid electrode of said tube to a point on said network, a direct current path connecting the anode of said tube to a point on said network and an alternating current path connecting said anode to a point on said network such that the voltage drop between said last named point and the cathode is equal to the voltage drop between the grid connection to said network and the cathode multiplied by the amplification factor of the tube.

9. In apparatus of the character described, a direct current network, means for connecting a source of potential in series therewith, a thermionic tube having anode, cathode and grid electrodes, means for connecting said cathode in parallel with a portion of said network, means for connecting said grid electrode to a point on said network negative with respect to said cathode, a direct current path connecting the anode of said tube to a positive point on said network and an alternating current path connecting said anode to a point on said network such that the voltage drop between said last named point and said cathode is equal to the voltage drop between said cathode and the point of connection of the grid to said network multiplied by the amplification factor of the tube.

10. In a cascade amplifier for audio frequency, a pair of thermionic tubes each having anode, cathode and grid electrodes, a resistance network, means for connecting the cathode of each of said tubes in parallel with different portions of said resistance network, means for connecting the grid of each of said tubes to a point on said resistance negative with respect to the points of connection between the cathodes and said network, a direct current path connecting the anode of each of said tubes to a point on said network positive with respect to the point of connection of said cathodes to said network, an alter-

nating current path connecting the anode of each of said tubes to said network at points so chosen with respect to the cathode connection of that tube, that the voltage drop between each of said points and the respective cathode connection to said network is equal to the voltage drop between each of said grid connections and the cathode of that tube multiplied by the amplification factor of that tube.

11. In combination, a resistance network, an electron discharge tube having its cathode connected to a point on said network, means for connecting the control electrode of the tube to a point on said network more negative than said first point, means for connecting the anode of the tube to a point on said network more positive than said first point, and additional means having a high impedance to direct current but a low impedance to alternating current of audible frequency for connecting said anode to a second point on said network less positive than said first anode connection point.

12. In combination, a resistance network, an electron discharge tube having its cathode connected to a point on said network, means for connecting the control electrode of the tube to a point on said network more negative than said first point, means for connecting the anode of the tube to a point on said network more positive than said first point, and additional means having a high impedance to direct current but a low impedance to alternating current of audible frequency for connecting said anode to a second point on said network less positive than said first anode connection point, there being a greater potential difference between the said second anode connection point and said cathode connection point than between said control electrode connection point and said cathode point.

13. In combination, a resistance network, an electron discharge tube having its cathode connected to a point on said network, means for connecting the control electrode of the tube to a point on said network more negative than said first point, means for connecting the anode of the tube to a point on said network more positive than said first point, and additional means having a high impedance to direct current but a low impedance to alternating current of audible frequency, and including a translating device, for connecting said anode to a second point on said network less positive than said first anode connection point.

14. In combination, a resistance network, an electron discharge tube having its cathode connected to a point on said network, means for connecting the control electrode of the tube to a point on said network more negative than said first point, means for connecting the anode of the tube to a point on

said network more positive than said first point, and additional means having a high impedance to direct current but a low impedance to alternating current of audible frequency for connecting said anode to a second point on said network less positive than said first anode connection point, there being a greater potential difference between the said second anode connection point and said cathode connection point than between said control electrode connection point and said cathode point, the ratio of these potential differences being approximately equal to the amplification constant of the tube.
